UNITED STATES PATENT OFFICE.

PAUL CHARLES WARNER, OF NEW ROCHELLE, AND ROBERT WILSON BLODGET, OF NEW YORK, N. Y.

SHIP'S PATCH.

1,301,204.

Specification of Letters Patent. Patented Apr. 22, 1919.

Application filed March 5, 1918. Serial No. 220,484.

To all whom it may concern:

Be it known that we, PAUL C. WARNER and ROBERT W. BLODGET, both citizens of the United States, and residents, respectively, of 5 New Rochelle, in the county of Westchester and State of New York, and of the city of New York, borough of Manhattan, in the county and State of New York, have invented a new and Improved Ship's Patch, of 10 which the following is a full, clear, and exact description.

Among the principal objects which the present invention has in view are: to provide means for closing a gap or leak in the hull 15 of a ship; to provide means for readily disposing the filling member in active service, to accommodate leaks or apertures of unascertained size and shape; to provide patches of the character mentioned which 20 are conveniently transported; and to provide a patch adapted for augmenting the flotation of a ship.

Drawings.

25 Figure 1 is a vertical cross section of the hull of a ship, showing a patch constructed and arranged in accordance with the present invention as actively applied to said ship;

Fig. 2 is a plan view of a vessel showing 30 the arrangement of patches in both the inactive and active positions thereof;

Fig. 3 is a detail view on an enlarged scale showing the side of a patch, the patch being partly cut away to show the interior 35 construction thereof;

Fig. 4 is an end view showing a patch inactively disposed on a carriage provided therefor, constructed and arranged in accordance with a modified form of the invention 40;

Fig. 5 is a side view of the same;

Fig. 6 is a side view showing a fragment 45 of the hull of a ship and a patch constructed and arranged in accordance with the present invention in service relation thereon.

Description.

As seen in the drawings, when the patch 11 is inactively disposed, it is preferably 50 rolled to form a bundle which is deposited on the trucks 12 and 13, as the case may be. Suitable lashings 14 or stakes 15 are provided for holding the bundles in position on the trucks. The trucks 12 and 13 are suitably mounted for movement over the deck

of the ship, to launch the patch 11 into position to cover the holes or damaged area. The trucks 12, as seen in the drawings, are provided with caster wheels 16, which provide sufficient flexibility of movement in the 60 trucks to admit of the same being quickly moved to any desired part of the deck. As seen best in Fig. 2 of the drawings, the trucks 12 are disposed inactively in position adjacent the center of the deck of the ship 65 17. The ship 17, when equipped with the trucks 12, is preferably provided with a central air supply pipe 18, which is connected with any suitable reservoir of air 33, or air-pumping system having outlet valves 19, 70 which are connected by means of flexible hose 20 with the patch or patches 11.

The patches 11 are flat hollow bags, the size of which is determined by experience, it being intended that they shall cover the apertures usually caused by accident or by an attack, such as that inflicted by a torpedo. The patch is provided with a screw-threaded nipple 21, which is connected by a suitable coupling with a hose 20. An eyelet 22 is 80 operatively connected by a cable 23, with a suitable windlass or winch 24. The cable 23 serves to govern the lengthwise position of the patch when adjusting the same to the damage inflicted on the ship's hull. 85

It will be understood that while there have been shown the patches with which the vessel is equipped, as being stowed on the deck thereof, they may be stowed between decks, it being intended to have them on deck only 90 when the vessel is passing through some recognized dangerous area.

In Figs. 4 to 6, a modified form of the invention is shown, wherein the elongated truck 13 is provided with suitable carriages 95 25. The carriages 25 are supported by wheels 26, which track upon rails 27. One of the rails 27, as seen best in Fig. 4 of the drawings, is disposed beyond the side of the ship's hull 17, and is there supported by a 100 series of brackets. The other rail 27 is preferably disposed inboard or within the outer surface of the hull of the ship. An overhanging guard rail 28 is disposed above each of the rails 27. 105

The carriages 25 are pivotally mounted at opposite ends of the truck 13 and the wheels of the said carriages are sufficiently closely related to permit the swinging of the carriages when the latter is moved around the 110

curved portions of the rails 27, where the same conform to the curvature of the stern of the ship's hull.

When using the modified form of the invention, the ship has a number of stand pipes 29, to the valves 30 of which is connected the hose pipe 31 with which each of the patches is furnished. The trucks 13 are drawn lengthwise of the ship and of the rails 27 thereon, by cables 32, said cables being wound on the winches 24 on the bow of the ship. To use patches constructed and arranged as disclosed, the trucks 12 or 13 are placed adjacent the bulwarks or bow of the ship. The cable 23 is made fast to the winch 24 and the patch 11 is thrown into the sea, the lashing 14 or stakes 15 having been removed as obstructions thereto. The patches 11 being constructed of relatively heavy material and completely deflated, have little or no buoyancy and therefore sink into the water into which they are thrust. The cables 23 are paid out until the patch 11 passes over the hole or opening made in the side of the ship. The inrushing water at this point carries the patch into the hole or opening. The patch is then raised by holding the cable 23,

and the valves 19 or 30 are opened to permit the air under pressure to enter the bag-like patch. The air is of sufficient pressure to 30 distend the bag until it completely covers and fills in the hole or aperture into which it has been drawn by the inrushing water. The current of water is in this manner, at least checked sufficiently to allow the introduction of mechanics for permitting the closure of said hole or aperture to make the ship seaworthy or to permit the ship to reach a port of safety. 35

Claims.

40

A ship's patch comprising a deflated, inflatable bag-like member, said bag-like member being adapted for introduction to the inside of a ship's hull through an aperture 45 in the wall thereof; means for arresting said member when partially in said hull; and means for inflating said member after the same has been disposed as mentioned, whereby said member is held by said aperture so 50 that said member cannot be ejected from said hull or forced thereinto.

PAUL CHARLES WARNER.
ROBERT WILSON BLODGET.
